UNITED STATES PATENT OFFICE.

JOHN SIMONS, OF ELIZABETH, NEW JERSEY, ASSIGNOR TO SAMUEL L. MOORE & SONS CORPORATION, OF ELIZABETH, NEW JERSEY, A CORPORATION OF NEW JERSEY.

EXPLOSIVE-ENGINE NOZZLE.

1,171,469.

Specification of Letters Patent. Patented Feb. 15, 1916.

Application filed March 11, 1912. Serial No. 682,945.

To all whom it may concern:

Be it known that I, JOHN SIMONS, of Elizabeth, in the county of Union, and in the State of New Jersey, have invented a 5 certain new and useful Improvement in Explosive-Engine Nozzles, and do hereby declare that the following is a full, clear, and exact description thereof.

My invention relates particularly to an 10 improvement in injector nozzles for explosive engines, which are designed more particularly for utilizing liquid fuels of the higher specific gravities, such, for example, as kerosene or crude oil. Hitherto in explosive engines which have been designed to use 15 liquid fuels of higher specific gravity, the ignition has been effected by injecting the charge of fuel into a small ball or dome attached to the cylinder of the engine and 20 which is heated by heat conducted from the engine cylinder and by the heat of the explosions within the cylinder.

One of the purposes of injecting the liquid 25 fuel into the small ball or dome has been to permit the engine to be readily started by previously heating the ball or dome by an extraneous source of heat, such as a gasolene torch. The constant injection of the liquid fuel into the ball or dome results in causing 30 the rapid accumulation of a thick deposit of carbon which covers up the interior of the ball or dome and thereby lessens the efficiency of the ball or dome as a starting device for the engine, and materially retards 35 the proper ignition of the successive charges of fuel in the cylinder, and also lessens the efficiency of the engine because of the imperfect combustion of the fuel injected. Furthermore, the injector nozzles which 40 have been hitherto used have been so constructed as to inject a quantity of liquid fuel having the nature of a solid jet of liquid or an approximation thereof, so that, as a consequence, a considerable portion of 45 the fluid does not have an opportunity to mix with the air in the cylinder before the ignition or exhaust of the ignited fuel, and so that, as a consequence, some of the fuel becomes carbonized before it can be ignited 50 on the interior of the cylinder, thereby lowering the efficiency of the engine, because of the imperfect combustion of the fuel and because of the accumulation of the carbon on the interior of the cylinder.

55 The object of my invention is to avoid

the difficulties and disadvantages above referred to.

A further object of my invention is to provide an injector nozzle which is so constructed that any air which may accumulate 60 within the nozzle to retard the proper distribution of the liquid fuel within the nozzle may be allowed to escape at any time.

In general, my invention comprises a construction whereby the charges of fuel are 65 not injected into the small dome or ball used to ignite the fuel, but are injected against a portion of the wall of the cylinder which is not cooled by the cooling jacket, and which is adjacent to the small dome or ball 70 so as to obtain the maximum heating effect both from the small dome or ball and from the explosion of the gases within the cylinder, without, at the same time, subjecting the fuel to the danger of carbonizing. 75

My invention comprises, furthermore, a construction by means of which the fuel is broken up into a finely atomized state before being injected into the cylinder, thereby avoiding the dangers above referred to. 80

My invention comprises also an injector nozzle whereby any air which may accumulate within the nozzle may be allowed to escape at any time.

I have shown an embodiment of my invention in the accompanying drawings, in which—

Figure 1 represents a vertical section of an explosive engine constructed in accordance with my invention; Fig. 2 is a vertical 90 section of the injector nozzle; and Fig. 3 is an enlargement of a detail of the injector.

In the drawings, 1 indicates an engine base having a crank casing 2 attached thereto, said casing inclosing in the usual manner a crank 3 carried by the main shaft, said shaft having a fly wheel 4 located upon the outside of the engine. The crank 3 is connected by means of a connecting rod 4^a, with a piston 5 which reciprocates within a cylinder 6. The cylinder 6 has near its lower end, an air inlet pipe 7. The air which is drawn into the engine through the air inlet 7 passes from the crank case 2 by means of a by-pass 8 and a port 9 into the cylinder 6 105 when the piston 5 is at the lower end of its path. An exhaust pipe 10 is attached to the cylinder at a point slightly above the position of the port 9, exhaust pipe 10 communicating with a valved outlet pipe 11 for the 110

water which is used for cooling the engine and which passes into a jacket 12 located around the cylinder 6 by means of an inlet pipe 13. The pipe 11 connects directly with 5 a jacket chamber 14 contained in a dome shaped cylinder head 15, closing the end of the cylinder, which chamber 14 connects with the jacket 12. The cylinder head 15 carries at its upper end a small dome or ball 16 which is attached thereto by means of 10 screws 17. The small dome or ball 16 is covered with a hood 18 having an aperture 19 in its side to receive a torch for starting the engine. At one side of the cylinder head 15 there is located an injector nozzle 20, which projects into the cylinder head through an extension 21 thereon, and which is attached to the extension 21 by means of screws 22.

As shown in Figs. 2 and 3, the nozzle 20 has a cylindrical body 23 into the rear of which is screw-threaded a valve casing 24 to the end of which is attached a supply pipe 25 for the oil to be fed into the cylinder. The valve casing 24 on its interior 25 carries a ball check valve 26. The valve 26 is normally maintained in position by the action of a spring 28 which is held against the valve 26 by a pin 29 passing through the valve casing 24 at the front end thereof. 30 To the center of the valve casing 24 there is attached an air valve which comprises a valve casing 30 having a central passage 31 which connects with a small aperture 32 leading to the outer air, and a needle valve 35 33 located on a thumb screw 34 which is adapted to normally close the passageway 31. At the front of the body 23 of the injector there is screw-threaded a nozzle head 35. The nozzle head 35 has a longitudinal 40 passageway passing through its center, this passageway comprising a rear chamber 36, a central restricted passageway 37 communicating with a conical valve seat 38 and an atomizing chamber 39, leading to the end of 45 the nozzle head. A valve 41 has a conical flange 42 fitting against the valve seat 38 and is provided with a plurality of longitudinal flattened portions 43 conveying the oil from the chamber 36 to the chamber 39. The conical flange 42 is normally maintained against the conical seat 38 through the action of a coiled spring 44 surrounding the valve 41, the end of the valve rod 41 being provided with one or more nuts to retain the spring 44 under tension. Screw-threaded into the passageway 40 there is an outlet nozzle 45, which nozzle has a central passage 46 communicating with the chamber 39, and an upwardly directed outlet aperture 47 so located as to 55 project the charges of fuel against the portion of the cylinder head 15 which is adjacent to the small dome or ball 16, but which is located above the upper end of the cooling chamber 14 carried by the cylinder head. 60

65 In the operation of my invention a torch

of any desired character, preferably a gaso-
len torch, is inserted through the opening
19 so as to cause the flame to impinge upon
the small dome or ball 16, thereby heating
it to a high temperature. When the small
dome or ball has been heated to redness the
70 fly wheel 4 is moved back and forth by hand
until sufficient momentum has been given to
the fly wheel to cause the air within the cyl-
inder to be compressed in the upper end of
the cylinder 6 and to cause a supply of
75 liquid fuel to be drawn in through the nozzle
20 and injected against that portion of the
cylinder head 15 which is located between
the small dome or ball 16 and the upper
80 portion of the cooling chamber 14. The
compression of the air and gases within the
cylinder 16 raises the temperature of the
air within the cylinder to a high point and
the heat thus produced, together with the
85 heat from the small dome or ball 16, results
in the ignition of the mixed air and atomized
fuel. The engine operates continuously and
the heat of the explosions and compressions
within the cylinder is sufficient to ignite the
90 successive charges of fuel without the pres-
ence of the torch within the hood 18. In the
operation of the engine upon the downward
stroke of the piston, the products of com-
bustion are exhausted through the exhaust
95 pipe 10 and the water which has been heated
by passing through the jacket of the engine
passes out also into the exhaust pipe 10
through the valved pipe 11. Upon the next
upward stroke of the piston 5 air is drawn
100 into the crank case 2 through the air inlet
pipe 7 and upon the next downward stroke
of the piston, the air which becomes trapped
and compressed within the crank case 2
passes upward through the by-pass 8 into
105 the cylinder 6 above the piston, and becomes
subsequently mixed with the injected oil as
it is pumped in successive charges by the
action of the engine through the supply pipe
25 in the usual manner. During the opera-
110 tion of the engine, the oil, which is prefer-
ably kerosene or crude oil, is forced into the
nozzle 20 against the action of the check
valve 26, and then into the chamber 36 and
along the flattened portions 43 of the valve
115 stem, which is located in the nozzle head 35.
The purpose of the flattened portions 43 is
to distribute the body of oil being injected
around the entire periphery of the conical
valve seat 38. Under the action of the force
120 of the oil which is pumped into the injector,
the conical flange 42 is forced to a small ex-
tent away from the conical valve seat 38,
thereby projecting the body of oil in a di-
verging conical spray into the chamber 39,
125 whereby the oil becomes effectively atomized
and broken into infinitesimally small drops.
The spray thus produced is conducted
through the outlet aperture 47 in the outlet
nozzle 45, from which it is projected against
130

the upper portion of the cylinder head previously referred to. It will be noted that as intimated above, the ignition takes place as a result of the injection of the atomized oil 5 against the portion of the cylinder head which is located between the small dome or ball 16 and the top of the cooling chamber 14. There is, consequently, no opportunity provided for the accumulation of a thick 10 layer of carbon in the small dome or ball 16, and at the same time the injected liquid fuel is subjected to the highest temperature obtainable within the cylinder by being injected against the surface in the cylinder 15 head above referred to.

While I have described my invention above in detail, I wish it to be understood that many changes may be made therein without departing from the spirit of my 20 invention.

I claim:

1. In a device of the character described, an injector nozzle, comprising a body, a head removably attached to said body and 25 having an interior spraying valve, and a restricted outlet opening located in a part removably attached to the valve head.

2. The combination of a combustion engine cylinder and an injector nozzle having 30 means attached thereto for permitting the escape of air before it reaches the outlet of the nozzle.

3. The combination of a combustion engine cylinder and an injector nozzle having 35 means attached thereto for permitting the escape of air before it reaches the outlet of the nozzle, comprising a hand valve.

4. The combination of a combustion engine cylinder and an injector nozzle having 40 means attached thereto for permitting the escape of air before it reaches the outlet of the nozzle, comprising a hand valve controlling an aperture leading to the outer air.

5. The combination of a combustion engine cylinder and an injector nozzle having 45 an interior spraying valve, a restricted outlet opening, and means attached thereto for permitting the escape of air before it reaches the outlet of the nozzle.

50 6. In a device of the character described,

an injector nozzle having a spraying valve, and means attached thereto for permitting the escape of air before it reaches said valve.

7. In a device of the character described, an injector nozzle having an interior spraying valve, and means attached thereto for permitting the escape of air before it reaches 55 said valve.

8. In a device of the character described, an injector nozzle having a spraying valve, 60 a restricted outlet opening, and means attached thereto for permitting the escape of air before it reaches said valve.

9. In a device of the character described, an injector nozzle having an interior spraying valve, a restricted outlet opening, and means attached thereto for permitting the escape of air before it reaches 65 said valve.

10. In a device of the character described, an injector nozzle having a spraying valve, 70 a spring normally pressing the valve against the seat, and means attached thereto for permitting the escape of air before it reaches said valve.

11. In a device of the character described, 75 an injector nozzle having an interior spraying valve, a spring normally pressing the valve against the seat, and means attached thereto for permitting the escape of air before it reaches said valve.

12. In a device of the character described, an injector nozzle having a spraying valve, a spring normally pressing the valve against the seat, a restricted outlet opening, and means attached thereto for permitting the 85 escape of air before it reaches said valve.

13. In a device of the character described, an injector nozzle having an interior spraying valve, a spring normally pressing the valve against the seat, a restricted outlet 0 opening, and means attached thereto for permitting the escape of air before it reaches said valve.

In testimony that I claim the foregoing I have hereunto set my hand.

JOHN SIMONS.
